Atty.

UNITED STATES PATENT OFFICE

FREDERICK M. DURKEE, OF BROOKLINE, MASSACHUSETTS

SAFETY RAZOR

Application filed September 28, 1928. Serial No. 309,094.

My invention relates to safety razors, and particularly to safety razors of that type including the well known Gillette safety razor, and it has for its object to provide an improved safety razor of this class.

Safety razors of the class indicated have heretofore been constructed so as to comprise several separable pieces which were not as conveniently handled in assembling, disassembling and cleaning the razor as might be desired. Moreover, when a razor of this class, as heretofore constructed, was opened or taken apart, the several elements thereof were entirely disconnected and one or more of them were liable to be misplaced, lost or damaged through being dropped. My invention has for its object to reduce to a minimum the number of separate parts, and in the best form of my invention I have provided a safety razor of the type indicated so constructed that when it is opened for the purpose of inserting or removing a blade, or for the purpose of cleaning, the several parts thereof remain connected together and the whole device can be conveniently manipulated and handled as a unit.

The invention consists in a safety razor having the peculiar features of construction and mode of operation set forth in the following description, the novel features thereof being particularly pointed out and defined in the claims at the close thereof.

In the accompanying drawings:

Figure 1 is an elevation, partly in section, of a safety razor constructed in accordance with my invention.

Figure 2 is a top plan view of the razor shown in Figure 1.

Figure 3 is an elevation, partly in section, of the handle and coupling member herein-after described.

Figure 4 is a central longitudinal sectional view of the movable jaw herein-after described.

Figure 5 is a plan view of the fixed jaw hereinafter described.

Figure 6 is a sectional view of the blade clamp.

Figure 7 is a plan view of the coupling member hereinafter described.

Figure 8 is a plan view of the blade constituting part of the razor shown in Figure 1.

Figure 9 illustrates the operation of my improved razor.

Figures 10 and 11 are enlarged sectional details also illustrating the operation of my improved razor.

The form of my invention illustrated in Figures 1 to 8 inclusive comprises a handle member 1, provided at one end with an interiorly threaded socket 2, said end being made exteriorly cylindrical to fit within the centrally disposed hole 3 of a coupling member 4 within which it is free to rotate. A pin or screw 5 mounted in the coupling member 4 has its inner end disposed within an annular groove 6 provided upon the exterior of the handle member 1, so that normally the coupling member 4 is locked to the handle member, but the latter is free to be rotated relatively to the former.

The coupling member 4 is made at opposite sides of the hole 3 with arms 7, 7 constructed with sockets 8, 8 to receive studs 9, 9 projecting from the concaved side of a transversely arcuate fixed clamp jaw 10, the arms 7, 7 being split longitudinally as at 11, 11, so that the studs 9 are gripped and held frictionally by said arms, thus providing for removal of the coupling member 4 from the studs 9 when desired.

The fixed clamp jaw 10 is made at its middle with a hole 12 through which projects a threaded stem 13 that is provided upon the concaved side of a transversely arcuate movable clamp jaw 14, and at opposite sides of said stem 13 are provided the usual dowel-receiving holes 15.

Projecting from the concaved side of the

transversely arcuate fixed jaw 10, one at each side of the hole 12, are two blade-positioning dowels 16 which occupy the holes 15 of the movable jaw 14 when the latter is in its closed position.

At one end thereof the fixed jaw 10 is made with an eye 17 hingedly connected with a similar eye 18 provided upon the adjacent end of the movable jaw 14, by means of a sheet-metal link 19. This link hinge 19 permanently connects the ends of the two jaws of the clamp and permits the movable jaw to be swung thereon toward and from the fixed jaw, and it is to be noted that it also provides sufficient play or lost motion to permit the threaded stem 13 of the movable jaw 14 to be passed freely into and out of the hole 12 of the fixed jaw, and to be screwed into the threaded socket 2 of the handle member 1.

20 The usual Gillette blade 20, Figure 8, is provided, and this blade is incorporated in the razor by placing the same against or upon the fixed jaw 10, with the studs 16 occupying the apertures 21 of the blade and with 25 the middle aperture 22 of the latter registering with the hole 12 of the fixed jaw 10. After placing the blade in position the movable jaw 14 is closed and by rotating the handle member 1 the stem 13 is screwed into the 30 socket 2, thus clamping the blade in position and flexing it to the desired extent.

The fixed jaw 10 is provided as usual with guard combs 31, and since the dowels 16 are, in the form of my invention shown in Figures 1 to 8 inclusive, rigid parts of said fixed jaw 10, it will be clear that the blade 20 when placed upon these dowels 16 will be accurately positioned with respect to the guard combs 31. This was not the case with safety 35 razors of this type as heretofore constructed where the dowels 16 were provided upon the movable jaw 14. Thus with the old construction there was necessarily play or looseness to some extent between the dowels on the movable jaw and the sides of the holes on the fixed jaw so that as a result the blade ordinarily would not be as accurately positioned with respect to the guard combs as is the case with my improved construction above described where the dowels 16 are part of the lower fixed jaw 10.

One of the principal advantages to the novel construction above described is the ease and despatch with which the blade can be removed from the device. In effecting the removal of the blade, the thumb of one hand is placed upon the top of the end of the razor blade that is opposite or farthest from the hinge, while the fingers of that hand are passed around the handle member with the forefinger immediately under the fixed jaw 10. Then, while exerting downward pressure with the thumb upon the end of the blade 20, the handle member 1 is unscrewed from the stem 13 and immediately that the

latter is free the upward spring of the blade, assisted by the downward pressure of the thumb, throws the movable jaw 14 upwardly and away from the fixed jaw into the position shown in Figure 9, leaving the razor 70 blade 20 canted upwardly as shown, so that it may be easily picked up and removed. It will thus be clear that the opening movement of the movable jaw 14 is effected more or less automatically by the upward pressure against 75 the same exerted by the razor blade while the latter is under the influence of the downward pressure of the thumb, so that it is only left for the operator to remove the blade from the razor.

80 From the above description it will be seen that the coupling member 4 and fixed jaw 10 provide a head for the handle or stem of the razor so that the latter is made up of two separable parts which is a feature of convenience in packaging and storing the razor.

85 Ordinarily, however, the parts 4 and 10 are left connected while the razor is in service since it is only necessary to open the jaw 14 and remove the blade in order to thoroughly 90 cleanse the structure after use.

95 The permanent link connection 19 connecting one end of jaw 14 with the head of the razor is an important feature of my invention which has the advantage that when the jaw 14 is swung down on to the blade in preparing the razor for use, the free end of the threaded stud 13 can be moved about laterally and entered properly within the threaded socket at the upper end of the handle 1 because of the flexibility provided by link 19. The lost motion at the link 19, referred to above, is also important for the reason that it permits of endwise or axial movement of the threaded stud 13 toward the handle 1, 100 when the latter is being screwed thereon to clamp the blade between the two jaws.

105 As will be seen by comparing Figs. 6 and 9, the link 19 and cross-bar 18 on jaw 14 are free to swing around the cross-bar of eye 17 when jaw 14 is swung from its closed to its widely open position. This is possible because of the slackness or lost motion provided by the link connection 19 so that when the free end of the stud 13 is being screwed into the socket 2 at the upper end of handle 1, the jaw 14 is brought down toward the fixed jaw 10 by a rectilinear bodily movement which bends the blade around the transversely arcuate fixed jaw 10.

110 It will therefore be clear that the peculiar link hinge connection which I have provided enables the transverse curvature of the razor blade to be regulated by rotative adjustment of the handle 1, thereby to adjust the cutting edges of the blade toward and from the serrated edges of the jaw 10.

115 In a razor of the class to which my invention relates the curvature of the blade is varied by rotative adjustment of the handle 1

to vary the cutting action of the blade, this rotative adjustment of the handle moving the opposite cutting edges of the blade toward or from the fixed jaw or guard 10 according 5 to the direction in which the handle is rotatively adjusted. When the handle 1 is screwed up tight the blade will not shave so close to the skin as when the handle is slightly unscrewed, and in practice about one 10 quarter of a revolution of the handle 1 is sufficient to adjust the blade 20 from a condition of maximum curvature to its condition of minimum curvature. That is the blade 20 is adjusted to its fullest extent by about 15 one quarter of a revolution of the handle 1. Of course, it is desirable that this movement of adjustment of the movable jaw 14 be made on a rectilinear path so that the blade will be flexed uniformly from end to end and not 20 more at one end than at the other as would be the case if there were no lost motion at the link 19. It is a feature of my invention that when the movable jaw 14 occupies its closed 25 position as shown in Figure 1, the link 19 is sufficiently loose to permit the movable jaw 14 to move slightly and bodily on a rectilinear path toward and from the fixed jaw 10. Thus when the handle 1 is screwed up tight 30 the link 19 is loose and there is sufficient lost motion at said link to permit the movable jaw 14 to move bodily on a rectilinear path away from the fixed jaw 10 during about one quarter of a revolution of the handle 1 in a direction to unscrew the same from the stem 35 13. Thus the curvature of the blade 20 of my new razor may be uniformly varied within limits to cause the same to shave roughly or to shave closely, as desired.

Figure 10 is an enlarged sectional detail 40 showing the relationship of the two jaws and link when the handle is screwed up tight and the blade is curved transversely to its maximum extent. In Figure 11 the movable jaw 14 is shown in the position to 45 which it is moved when the handle is unscrewed to the extent of about one quarter of a revolution and this is the relationship of the parts when the opposite cutting edges of the blade are at the limit of their movement away from the fixed jaw or guard 10 50 and are adjusted for a close shave. In Figure 10 the movable jaw 14 occupies its fully closed position and it will be noted that the two bars 17 and 18 do not abut both 55 ends of the link so that there is spaced at *a* which permits the movable jaw 14 to be adjusted bodily relatively to the fixed jaw 10 on a rectilinear path from the position shown in Figure 10 to the position shown in 60 Figure 11. Thus the cutting effects of the blade can, by adjustment of the handle, be varied within the limits determined by the length of the link 19.

What I claim is:

65 1. In a safety razor of the character de-

scribed the combination with a fixed jaw having a transversely arcuate convex blade-engaging face and a movable jaw having a transversely arcuate concaved blade-engaging face adapted to receive and hold between them a thin flexible spring sheet metal blade, 70 said jaws being provided at proximate ends each with a cross-bar, of a handle member projecting perpendicularly away from the outer side of said fixed jaw with which latter said handle member is rotatably connected, said handle member being adapted at its inner end to separably engage said movable jaw and when engaged therewith to maintain the same in blade-holding position while said handle member is manually rotated in either direction within predetermined limits thereby to adjust said movable jaw bodily on a rectilinear path relatively 75 to the fixed jaw to vary the cutting action of said blade and when rotated to a greater extent in one of said directions to free said movable jaw, and a link member made with an elongate slot loosely occupied by both of 80 said cross-bars so that said link member permanently connects said two jaws, the length of said slot permitting said movable jaw to be adjusted on said rectilinear path toward and from said fixed jaw independently of 85 said link member by said handle when the latter is rotatably adjusted within said predetermined limits to vary the cutting action of the blade.

2. A safety razor of the character described having its blade-holding jaws made each with a cross-bar at one end thereof, and a link member made with an elongate slot loosely occupied by both of said cross-bars so that said link member permanently connects said two jaws, the length of said slot 100 permitting said movable jaw to be adjusted bodily on a rectilinear path toward and from said fixed jaw independently of said link member when the razor is adjusted to vary the cutting action of its blade from maximum to minimum and vice versa.

3. A safety razor of the character described constructed in accordance with claim 2 wherein the fit of the cross-bars within the elongate slot of said link member is loose so 105 as to permit of universal movement of said movable jaw relatively to said fixed jaw while said movable jaw occupies its open position.

4. A safety razor of the character described comprising two transversely arcuate blade-holding jaws and a link member made with an elongate slot loosely and permanently occupied by transversely extending end portions of said two jaws, the length of said 115 slot permitting one of said jaws to be adjusted bodily on a rectilinear path while maintained parallel with the other jaw toward and from the latter independently of 120 said link member when the razor is adjusted 125

to vary the cutting action of its blade from maximum to minimum and vice versa.

5. A safety razor of the character described constructed in accordance with claim 4 wherein the fit of said transversely extending end portions within the elongate slot of the link is loose so as to permit of universal movement of said adjustable jaw relatively to the other jaw while said adjustable jaw occupies its open position.

10 Signed by me at Boston, county of Suffolk and State of Massachusetts, this 25th day of September, 1928.

FREDERICK M. DURKEE.
